ABSTRACT

Apparatus for deflecting the beam of an electron beam welding device, or similar source of a beam of radiant energy. The apparatus comprises a sine/cosine wave generator and a triangular/rectangular wave generator selectively connectable to the inputs of a bi-channel amplifier whose output is connected, for example, to the deflection coils, or plates, of the electron beam device. Circuitry is provided to obtain either a frequency or amplitude modulation of the deflection currents or voltages supplied to the deflection coils or plates of the device.

ELECTRON BEAM DEFLECTION APPARATUS

BACKGROUND OF THE INVENTION

1. Field of the Invention

Broadly speaking, this invention relates to deflection generators. More particularly, in a preferred embodiment, this invention relates to a deflection generator for deflecting a beam of radiant energy along a plurality of predetermined trajectories. The invention is particularly suited for deflecting the beam of an electron beam welding apparatus with respect to the workpiece to be welded.

2. Discussion of the Prior Art

The vast majority of bonding interfaces found in industry are, because of production problems, relatively simple curves, such as straight lines, circles, ellipses, etc. or curves made up from elements of the listed basic curves. When bonding such interfaces by means of an electron beam apparatus, for example, it is, of course, necessary to move the electron beam, relative to the workpiece, so that the focused electron beam traverses the desired curve defined by the bonding interface.

One way to do this is to place the workpiece on a table, which is adopted for translation in the X-Y plane, beneath the focused electron beam. The table is then displaced manually, or automatically, while visual inspection of the weldment is continuously made. Unfortunately, this technique works well for only the more simple curves and, in any event, is not suitable for large scale production.

Because a focused electron beam has a relatively narrow cross-section, it is known in the art to "wobble" the electron beam from side to side, in order to provide some heating or melting of areas immediately adjacent the bonding interface. In the prior art, such a "wobble" has been provided by applying the A. C. mains to the electron beam deflecting coils via a suitable potentiometer. Unfortunately, the frequency of the A.C. mains (50 to 60 HZ) is too low for this application and it has proven necessary to move the X-Y table from side to side if this highly advantageous supplementary heating is desired.

It has been proposed in the past to use conventional L-C and R-C oscillators of higher frequency to provide this highly desirable beam "wobble" and/or to deflect an electron beam in a circular or elliptical trajectory or any combination thereof. Unfortunately, the results which have been obtained with these conventional oscillators have not been satisfactory, due to the relatively high harmonic and phase distortion present in the output signal. Further, these prior art oscillators exhibit an undesirable inter-relationship between frequency and amplitude such that a two-dimensional representation of the desired curves is impossible, with the accuracy required for the welding. The prior art oscillators are also unable to provide stable output signals at a frequency low enough to satisfy the requirements of a large electron beam welding apparatus.

The problem, then, is to find a deflection generator for an electron beam apparatus, or other radiant energy source, which will generate deflection currents (or voltages) to cause the electron beam to traverse circular or elliptical trajectories or any combination thereof, with minimal error and distortion. The generator should also be capable of "wobbling" the beam either along, or transverse to, the trajectory and should be capable of operating over an extremely wide frequency band, without sacrificing the low distortion qualities of the deflection current, or voltage.

SUMMARY OF THE INVENTION

This problem has been solved by the instant invention which, in a preferred embodiment comprises at least one generator for generating at least one output signal of a predetermined and stabilized amplitude, frequency and phase; a stabilized, bi-channel output amplifier; deflection apparatus, connected to the output of the stabilized output amplifier; and circuitry, connecting the output signal or signals to the input of the bi-channel amplifier, so that an amplified replica of the output signal or signals is impressed across the deflection apparatus to controllably deflect the radiant energy beam.

DESCRIPTION OF THE DRAWINGS

FIG. 1 is a block diagram of an illustrative deflection generator according to this invention;

FIG. 2 is a schematic drawing of an illustrative sine/cosine generator for use with the deflection generator of FIG. 1;

FIG. 3 is a schematic drawing of an illustrative triangular/rectangular wave generator for use with the deflection generator of FIG. 1;

10 FIG. 4 is a schematic drawing of an illustrative frequency modulating circuit for use with the sine/cosine generator of FIG. 2;

15 FIG. 5 is a schematic drawing of an illustrative amplitude modulating circuit for use with the sine/cosine generator of FIG. 2.

DETAILED DESCRIPTION OF THE INVENTION

FIG. 1 is a block diagram of an illustrative deflection generator, according to the invention. One skilled in the art

20 will appreciate that the generator shown is equally suited for electrostatic as well as electromagnetic deflection. As shown in FIG. 1, the deflection generator comprises two individual generators; a sine/cosine generator 1 and a triangular/rectangular wave generator 5. The sine/cosine generator 1 is connected to an amplitude controller 2 and has two output connections 3 and 4 on which the sine wave and cosine wave

25 signals appear, respectively. In similar fashion, triangular/rectangular wave generator 5 has two output connections 6 and 7 on which the triangular wave and rectangular wave

30 signals appear, respectively. The outputs of generators 1 and 5 are connected to a function selector 8 which selects the desired waveform, under control of an operator, and passes it to one input 9, 10 of a pair of output amplifiers 11 and 12, respectively. The current stabilized outputs of output amplifiers 11 and 12 are connected, in turn, to a pair of deflection coils 13 and 14, respectively, which are associated with the electron beam apparatus (not shown since it is conventional).

35 One side of deflection coil 13 and 14 is connected to ground, via a shunt resistor 15 and 16, respectively. A limit indicating circuit 18 is connected to the outputs of the two output amplifiers, 11 and 12, and to a warning indicator bulb 19 so that when the output voltage of either amplifier reaches some predetermined value, the limit indicating circuit lights the warning lamp.

40 A pair of adjustable d. c. voltage sources 22 and 23 are connected to output amplifiers 11 and 12, respectively, to permit the operator to adjust the position of the electron beam on the workpiece, in the same way that the trace of an oscilloscope can be centered on the scope screen.

50 Turning now to FIG. 2, sine/cosine generator 1 comprises a pair of serially connected operational amplifiers 30 and 31, which function as integrating circuits. A third operational amplifier 32, acting as an inverting stage, is connected in the feedback path which interconnects the output of operational amplifier 31 and the input of operational amplifier 30. This configuration represents a self-oscillating system with the result that a sinewave signal appears at the output 3 of operational amplifier 30 while a signal delayed by $\pi/2$, or a cosine wave, appears at the output 4 of operational amplifier 31. The 55 frequency at which the system oscillates is determined by the parameters of a pair of load resistors 33 and 34, the value of a plurality of capacitors 35-43 and 36-44 and by a pair of voltage dividers 45 and 46 in the feedback paths associated with operational amplifiers 30 and 31, respectively.

60 Capacitors 35, 37, 39, 41 and 43 and capacitors 36, 38, 40, 42 and 44 are of paired, equal values and are, advantageously, arranged in decade increments. A ganged stepping switch 47 can connect a corresponding pair of capacitors to the respective feedback loop. Thus, if the capacitors increase in decade fashion, rotation of switch 47 will result in tenfold changes in frequency of the system. The two voltage dividers 45 and 46 are of equal value and are advantageously formed from a ganged pair of potentiometers. Voltage dividers 45 and 46 serve to provide a continuous frequency adjustment, within any given decade.

Oscillations are initiated in the system by temporarily connecting the output 56 of operational amplifier 32 to the input 48 of operational amplifier 31. To obtain stable oscillations of constant amplitude a well defined feedback coefficient is required, which is, of course, provided by the amplitude controller 2 (FIG. 1).

Rapid build-up of the amplitude of the oscillations in the circuit may be obtained if, shortly after the apparatus is turned on, and, therefore, shortly after the supply voltage is applied to power supply terminal 49, capacitor 37, for example, associated with one of the feedback loops is charged to a voltage which is determined by a third voltage divider 50 which is connected to the power supply terminal 49.

The circuit further comprises a transistor 53 whose emitter is connected to ground and whose base is connected to the midpoint of a capacitor 51 and a resistor 52 serially connected between ground and the power source. After the supply voltage is turned on, capacitor 51 charges through resistor 52. Thus, the base of transistor 53 becomes positive for a time period determined primarily by the time-constant of resistor 52 and capacitor 51. During the interval when the base of transistor 53 is positive, the transistor is biased "on" and a relay 54 in the collector circuit thereof is operated. Relay 54, operated, provides the desired path between voltage divider 50 and capacitor 37, say, for fast warm-up. When capacitor 51 becomes fully charged, transistor 53 turns "off," releasing relay 54 and breaking the path from voltage divider 50 to capacitor 37.

FIG. 3 depicts the schematic of an illustrative triangular/rectangular wave generator 5. As shown, the generator comprises the serial connection of an inverting, integrating stage 60, a hysteresis switching stage 62, a pulse-shaping stage 63, a wave-shaping stage 64, and a symmetrical output stage 65.

The inverting, integrating stage 60 includes an operational amplifier 61 which serves to integrate any d. c. voltage applied thereto (e.g., a negative d.c. potential) and thus produces at its output terminal 66 a steadily increasing ramp potential of opposite polarity. The ramp voltage appearing on terminal 66 is also fed to the input of the hysteresis switch stage 62.

This latter stage includes a pair of interconnected transistors 67 and 68 which interchange their normally conducting and non-conducting states when the input voltage (from output 66 of stage 60) reaches some predetermined level. The signal which is produced when hysteresis switch 62 changes state is shaped by pulse-shaping stage 63, rendered symmetrical by wave-shaping stage 64 and amplified by output stage 65. The amplified signal is fed back over a feed-back loop to the input of integrating stage 60 as a positive signal. This, in turn, generates a steadily decreasing ramp voltage at output terminal 66, starting with the final value reached at the instant that hysteresis switch 62 changes state.

The decreasing ramp voltage at terminal 66 is fed, as before, to the hysteresis switch 62 and when a predetermined negative limit is reached, the transistors 67 and 68 again change state, and the process repeats ad infinitum. Thus, the output voltage which appears across terminal 66, as a function of time, will assume a triangular waveform. Correspondingly, the waveform which will appear across the output 69, of the symmetrical output stage 65, will reflect the state of the hysteresis switch and will, thus, be a rectangular wave of the same frequency as the triangular wave.

A variable resistor 70 connected in the supply path from battery terminal 82 to the transistors 67 and 68 controls the threshold switching voltage of switch 62. A resistor 71 of negative temperature coefficient, in the same path, compensates for temperature current-drift in transistor 67. A pair of Zener diodes 72 and 73, in the output of amplifier stage 65, ensure the symmetry of the rectangular output wave, relative to ground, as well as its amplitude stability.

Because of the symmetry and stability of the rectangular output wave, integrating stage 60 produces a triangular wave at output 66 which is also symmetrical with respect to ground. Furthermore, both waves are extremely stable in frequency as

the rise time of the triangular wave depends directly on the amplitude of the rectangular wave.

The frequency at which generator 5 oscillates is determined by the values of capacitors 72 to 76 in the feedback loop of operational amplifier 61, as well as on a charging resistor 77 and a pair of potentiometers 78 and 79 which are connected to the input and output, respectively, of operational amplifier 61.

As before, capacitors 72 to 76 advantageously increase in value in decade fashion and are inserted into the feedback loop by a stepping switch 80. Thus, rotation of switch 80 will change the frequency of oscillation by powers of 10. Advantageously, potentiometer 78 may be used to adjust the frequency within any given decade, while potentiometer 79 may be used to provide a continuous adjustment of the amplitude of the triangular and rectangular output waves. D.C. supply potentials of equal but opposite polarity, with respect to ground, are connected to power supply terminals 81 — 81 (+ve) and 82 — 82 (-ve).

FIG. 4 illustrates an additional embodiment of the invention which may be used when it is desired to superimpose some frequency modulation on the sine and cosine waves produced by generator 1 (FIG. 2). As shown, potentiometers 45 and 46 of FIG. 2 are replaced by a pair of analog multiplying stages 90 and 91, respectively.

Thus, one input to analog multiplying stage 90 comprises the output 56 of the immediately preceding operational amplifier and the corresponding output of multiplying stage 90 is connected to load resistor 33. In like manner, multiplying stage 91 interconnects output 57 and load resistor 34.

The other input of both amplifying stages 90 and 91 is connected, in common, to the output of an additional operational amplifier 92, which functions as an adder stage. One input to operational amplifier 92 is connected through a potentiometer 93 to a d.c. source, while at least one other input 94 is connected to the source of the modulating signal. Potentiometer 93 is used to select the basic frequency of the sine/cosine generator (FIG. 2), preferably within one of the decades. Thus, application of a modulating voltage to terminal 94 will modulate the sinusoidal or co-sinusoidal current in the electron-beam deflection coils, resulting in a corresponding modulation of the circular trajectory of the electron beam on the surface of the workpiece. In an extreme case, this modulation can reverse the motion of the beam along the trajectory. Such a "wobble" in the beam path along the welding interface can considerably improve the strength and quality of the weldment. The apparatus of FIG. 4 may, of course, be associated with the triangular/rectangular wave generator of FIG. 3 by replacing, for example, potentiometer 78 therein.

FIG. 5 depicts yet another embodiment of the invention which may be used if amplitude rather than frequency modulation is desired. Amplitude modulation of the output signals from the sine/cosine generator will result in a corresponding modulation in the radius of the circle traced by the electron beam on the workpiece, for example.

As shown in FIG. 5, the sine and cosine outputs from generator 1 (FIG. 2) on terminals 3 and 4 are applied to input terminals 9 and 10 of output amplifiers 11 and 12 (FIG. 1), respectively. The signals on terminals 3 and 4 are applied to amplifiers 11 and 12 through a pair of equal value resistors 100 and 101, respectively, and also to one input of a pair of analog multiplying stages 102 and 103, respectively.

The outputs of multiplying stages 102 and 103 are connected by a second pair of equal value resistors 104 and 105, to the inputs 9 and 10 of amplifiers 11 and 12, respectively. The outer inputs 106 and 107 to multiplying stages 102 and 103, respectively, are connected, in common, to the source of modulating voltage, advantageously a completely separate generator. Resistors 100 and 104 and 101 and 105 sum whatever inputs are connected thereto. Thus the output of amplifier 11, for example, is the sum of the sine wave on terminal 3 together with the product of the sine wave on terminal 3 and the modulating voltage. The net effect is to vary the amplitude

of the sine wave output from amplifier 11 by the modulating voltage. The apparatus of FIG. 5 may also be utilized with the triangular/rectangular wave generator of FIG. 3 by connecting terminals 6 and 7 thereto, rather than terminals 3 and 4 shown in FIG. 5.

The above description of a preferred embodiment of the invention is set in the context of electromagnetic deflection of an electron beam machine. One skilled in the art will appreciate that only minor changes are necessary to use the invention with an electrostatically deflected electron beam machine. It will, likewise, be apparent that the invention is not limited in any way to the deflection of an electron beam, but, with appropriate minor modifications, could be used equally well to deflect a light beam, a sound beam or a beam of gamma particles, etc.

What is claimed is:

1. Apparatus for controllably deflecting a radiant energy beam, which comprises:
  - a stabilized, bi-channel output amplifier;
  - a pair of orthogonally oriented electromagnetic deflection coils for deflecting said beam, said coils being connected to the respective output terminal of said bi-channel amplifier; and
  - at least one generator having its output terminal connected to the input terminal of said bi-channel amplifier, said at least one generator including:
    - a first operational amplifier;
    - a first integrator comprising a second operational amplifier, a first plurality of capacitors and first switching means for selectively connecting one of said first plurality of capacitors as a feedback connection from the output of said second operational amplifier to the input thereof;
    - a second integrator comprising a third operational amplifier, a second plurality of capacitors and second switching means, ganged mechanically to said first switching means, for selectively connecting one of said second plurality of capacitors as a feedback connection from the output of said third operational amplifier to the input thereof;
    - a first voltage divider connected between the output of said first operational amplifier and ground, the center tap of said voltage divider being connected to the input of said first integrator;
    - a second voltage divider, mechanically ganged to said first voltage divider, connected between the output of said first integrator and ground, the center tap of said second voltage divider being connected to the input of said second integrator;
    - means for connecting the output of said second integrator to the input of said first operational amplifier to form a closed, oscillatory loop, coarse adjustment of the frequency of oscillation thereof being effected by said first and second switching means, and fine adjustment thereof by said first and second voltage dividers, the output signal of said at least one generator having a sinusoidal wave form and deriving from the output of said first integrator, the output of said second integrator yielding a second output signal, co-sinusoidal in wave form.
2. The deflecting apparatus according to claim 1, further comprising:
  - a resistor and a capacitor, serially connected between ground and the d.c. supply for said generator, to form an R-C timing circuit;
  - a transistor in common emitter configuration with its emitter connected to ground, its collector connected to said d.c. source, and its base connected to the juncture of said resistor and said capacitor;
  - a third voltage divider connected between said d.c. source and ground; and
  - a relay having its armature connected in the collector circuit of said transistor and a normally open pair of relay contacts connecting the center tap of said third voltage divider to the particular one of said first plurality of capacitors selected by said first switching means, whereby as said serially connected capacitor charges through said resistor, said transistor is biased into conduction thereby operating said relay and charging said selected capacitor through said pair of relay contacts.

3. Apparatus for controllably deflecting a radiant energy beam, which comprises:

- a stabilized, bi-channel output amplifier;
- a pair of orthogonally oriented electromagnetic deflection coils for deflecting said beam, said coils being connected to the respective output terminal of said bi-channel amplifier; and

at least one generator having its output terminal connected to the input terminal of said bi-channel amplifier, said at least one generator including:

- a first operational amplifier;
- a first integrator comprising a second operational amplifier, a first plurality of capacitors and first switching means for selectively connecting one of said first plurality of capacitors as a feedback connection from the output of said second operational amplifier to the input thereof;

a second integrator comprising a third operational amplifier, a second plurality of capacitors and second switching means, ganged mechanically to said first switching means, for selectively connecting one of said second plurality of capacitors as a feedback connection from the output of said third operational amplifier to the input thereof;

a first analog multiplier having two inputs and an output, the output being connected to the input of said first integrator, and one input of said analog multiplier being connected to the output of said first operational amplifier;

a second analog multiplier having two inputs and an output, the last-mentioned output being connected to the input of said second integrator, and one input of said second analog multiplier being connected to the output of said first integrator;

a fourth voltage divider connected between ground and the d.c. source for said generator;

an adder circuit having an output and two inputs, the output of said adder circuit being connected to the other inputs of both said first and said second analog multipliers, one input of said adder circuit being connected to ground, the other input of said adder circuit being connected to the center tap of said fourth voltage divider;

means, also connected to the other input of said adder circuit, for supplying an external frequency modulating signal to said generator;

means for connecting the output of said second integrator to the input of said first operational amplifier to form a closed, oscillatory loop, the coarse adjustment of the frequency of oscillation thereof being effected by said first and second switching means, and fine adjustment of said frequency being effected by said fourth voltage divider, the output signal of said at least one generator having a sinusoidal wave form, modulated by said modulating signal, and deriving from the output of said first integrator, the output of said second integrator yielding a second output signal, in modulated, co-sinusoidal wave form.

4. The apparatus according to claim 3, further comprising:

- third and fourth analog multipliers, each having an output and two inputs, the outputs of said first and second integrators being connected, via equal second and third resistors, to the first and second inputs, respectively, of said bi-channel amplifier and to one input of each of said third and fourth analog multipliers, the outputs of said third and fourth analog multipliers being connected, via fourth

and fifth identical resistors, to the first and second inputs, respectively, of said bi-channel amplifier; and means, connected simultaneously, to the other inputs of said third and fourth analog multipliers, for supplying an external source of amplitude modulating signals.

5. Apparatus for controllably deflecting a radiant energy beam, which comprises:
 a stabilized, bi-channel output amplifier;
 a pair of orthogonally oriented electromagnetic deflection coils for deflecting said beam, said coils being connected to the respective output terminals of said bi-channel amplifier; and
 at least one generator having its output terminal connected to the input terminal of said bi-channel amplifier, said at least one generator including:
 an inverting, integrating stage including a fourth operational amplifier, a plurality of capacitors, and third switching means for selectively connecting one of said plurality of capacitors as a feedback connection between the output and the input of said fourth operational amplifier;
 a hysteresis switching circuit connected to the output of said integrating stage;
 a pulse shaping circuit connected to the output of said hysteresis switching circuit; and
 a fifth voltage divider connected between ground and the amplified output of said pulse shaping circuit, the center tap of said fifth voltage divider being connected to an input of said integrating stage, the connection completing a closed oscillatory loop, the frequency of oscillation being coarsely determined by said third switching means and finely by said fifth voltage divider, the output signal of said at least one generator having a triangular wave form and deriving from the output of said integrating stage, the amplified output of said pulse shaping circuit yielding a second output signal, rectangular in wave form. 35

6. Apparatus for controllably deflecting a radiant energy beam, which comprises:
 a stabilized, bi-channel output amplifier;
 a pair of orthogonally oriented electromagnetic deflection coils for deflecting said beam, said coils being connected to the respective output terminals of said bi-channel amplifier; and
 at least one generator having its output terminal connected to the input terminal of said bi-channel amplifier, said at least one generator including:
 an inverting, integrating stage including a fourth operational amplifier, a plurality of capacitors, and third switching

means for selectively connecting one of said plurality of capacitors as a feedback connection between the output and the input of said fourth operational amplifier;
 a hysteresis switching circuit connected to the output of said integrating stage;
 a pulse shaping circuit connected to the output of said hysteresis switching circuit;
 a third analog multiplier stage having two inputs and an output, the output being connected to the input of said inverting, integrating circuit, and one input thereof being connected to the amplified output of said pulse shaping circuit;
 a sixth voltage divider connected between ground and the d.c. source for said generator;
 an adder circuit having an output and two inputs, the output thereof being connected to the other input of said third analog multiplier, one input of said adder circuit being connected to ground, the other input of said adder circuit being connected to the center tap of said sixth voltage divider;
 means, also connected to the other input of said adder circuit, for supplying an external frequency modulating signal to said generator;
 said adder circuit and third analog multiplier stage completing a closed, oscillatory loop, the coarse adjustment of the frequency of oscillation thereof being effected by said third switching means and fine adjustment being effected by said sixth voltage divider, the output signal of said at least one generator being triangular in wave form, modulated by said modulating signal, the output of said pulse shaping circuit yielding a second output signal in modulated, rectangular form.

7. The apparatus according to claim 5, further comprising:
 fifth and sixth analog multipliers each having an output and two inputs, the outputs of said integrating stage and said pulse shaping stage being connected, via equal sixth and seventh resistors, to the first and second inputs, respectively, of said bi-channel amplifier and to one input of said fifth and sixth analog multipliers, respectively, the output of said fifth and sixth analog multipliers being connected by eighth and ninth identical resistors, to the first and second inputs, respectively, of said bi-channel amplifier; and
 means, connected simultaneously, to the other inputs of said fifth and sixth analog multipliers, for supplying an external source of amplitude modulating signals.
